(57) **CLAIM**

We claim the ornamental design for a tray for a tray for a trolley, as shown and described.

DESCRIPTION

FIG. 1 is a top, front, right perspective view of a tray for trolley showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom, rear, right perspective view thereof; and, FIG. 9 is a top, front, right perspective view showing the tray for trolley in use.

The broken lines in the drawings illustrate portions of the tray for trolley which form no part of the claimed design.
